Primary Examiner — Susan M Lee*Assistant Examiner* — Linda G Brooks(74) *Attorney, Agent, or Firm* — SAIDMAN Designlaw Group(57) **CLAIM**

The ornamental design for a horse bit, as shown and described.

DESCRIPTION

FIG. 1 is a perspective view of a first embodiment of horse bit showing my new design;

FIG. 2 is a top view thereof;

FIG. 3 is a front view thereof;

FIG. 4 is a bottom view thereof;

FIG. 5 is a rear view thereof;

FIG. 6 is a left side view thereof, the right side view being a mirror image;

FIG. 7 is a perspective view of a second embodiment thereof;

FIG. 8 is a top view thereof;

FIG. 9 is a front view thereof;

FIG. 10 is a bottom view thereof;

FIG. 11 is a rear view thereof; and,

FIG. 12 is a left side view thereof, the right side view being a mirror image.

The broken lines illustrate portions of the horse bit and form no part of the claimed design.
